UNITED STATES PATENT OFFICE.

SAMUEL MOORE, OF PROVIDENCE, RHODE ISLAND.

MANUFACTURE OF DRILLS.

SPECIFICATION forming part of Letters Patent No. 315,530, dated April 14, 1885.

Application filed January 23, 1885. (No model.)

To all whom it may concern:

Be it known that I, SAMUEL MOORE, a citizen of the United States, residing in the city and county of Providence, in the State of Rhode Island, have made certain new and useful Improvements in the Manufacture of Twist-Drills, of which the following is a specification.

Prior to my invention in the manufacture of twist-drills cylindrical blanks somewhat longer than it was intended to have the finished drill were passed a number of times between two convex-faced rolls to form a groove in two sides or faces of the blank. After the blank with its grooves had thus been brought down to the requisite thinness, the drill was twisted into spiral form, and the end cut off and ground. This process has in practical use been found to be unsatisfactory and expensive. The blank being cylindrical, it has been found almost impracticable to start in and roll it down to an even thickness on each edge by the use of convex-faced rolls, and in passing out from between the rolls the blank was frequently destroyed, and always more or less injured by the rolls nipping or mashing down the end of the blank, necessitating the cutting off of quite a large piece of the end of the blank after rolling, thereby wasting the stock and enhancing the cost of manufacture. Inventive thought and skill have therefore been directed to the prevention of this waste and to the devising of means of rolling and grooving the blank so that it will be of an even and uniform thickness. The process of milling the drill from a blank has been resorted to at a sacrifice of metal in the body of the drill, and a consequent impairment of its strength and durability.

In my invention the cylindrical blank is rolled first between flat rolls to face it on two sides and bring it to a uniform thickness. The flattened blank is then passed between rolls with slightly convex faces to start the groove therein, and then rolls with more decided convex faces are used to complete the groove.

It must be understood that I use a blank of sufficient length to form two drills and the shanks of each. The rolls, both flat and convex, engage and leave the blank at a sufficient distance from either end thereof to form a shank on each end of the blank for each drill.

Of course any desired concavity can be imparted to the faces of the blank by the rolls, after which the blank is twisted into spiral form and cut into two equal parts. The ends are then properly ground and two drills are formed without loss of material or sacrifice of strength in any part of the drill, and the lips are even and of uniform thickness throughout, preserving this uniformity while being twisted, and consequently do not require so much grinding to bring them to an even and true finish. By using a blank long enough to make two drills as described I am enabled to bring each end of the blank to a finish before rolling, thereby affording two true centers, by which the blank can be centered and rolled and twisted uniformly.

In the drawings, Figure 1 is a top plan of the blank after it has passed through the flat rolls. Fig. 2 is a transverse section of same on line *o o*. Fig. 3 shows the blank grooved. Fig. 4 is a transverse section of same on line *x x* of Fig. 1. Fig. 5 shows the blank twisted into spiral form, and Fig. 6 shows a completed drill formed by dividing Fig. 5 centrally on line *y y*.

A represents the body of the blank provided with shanks *b b*. The body *A* is flattened, grooved, and twisted into the spiral form, as shown, the shanks *b b* forming in the completed stage the shanks of the drills. After the blank is twisted into the form shown in Fig. 5, it is divided on the line *y y* into two equal parts, the ends of each part are ground and pointed, and two completed drills are produced at one operation.

I claim as new herein and my invention and desire to secure by Letters Patent—

The method described of manufacturing twist-drills, the same consisting in rolling a blank into the forms shown in Figs. 1 and 3, with a shank at each end, and twisting such blank into the form shown in Fig. 5, dividing the same into two equal sections on the transverse line *y y*, to form two drills at each operation from a single blank, as set forth.

In testimony whereof I have hereunto set my hand, in presence of two witnesses, this 21st day of January, 1885.

SAMUEL MOORE
